(57) **CLAIM**

The ornamental design for a bottle holder for a modular filling station for filling syringes, as shown and described.

DESCRIPTION

FIG. 1 is a top front perspective view of the bottle holder of the modular filling station of the invention.

FIG. 2 is a left side view of the bottle holder of the modular filling station, the right side view being a mirror image thereto.

FIG. 3 is a top rear perspective view of the bottle holder of the modular filling station.

FIG. 4 is a top view of the bottle holder of the modular filling station.

FIG. 5 is a bottom view of the bottle holder of the modular filling station.

FIG. 6 is a front view of the bottle holder of the modular filling station.

FIG. 7 is a bottom front perspective view of the bottle holder of the modular filling station.

FIG. 8 is a rear view of the bottle holder of the modular filling station; and,

FIG. 9 is a bottom rear perspective view of the bottle holder of the modular filling station.

The dashed lines in FIGS. 1, 3 and 5-9 represent the fastener holes in the bottom and back of the bottle holder and form no part of the claimed design.

The claimed bottle holder for a modular filling station is for use in filling a syringe, in particular in dental applications. The modular filling station includes a dispenser head, a bottle holder, which can be used in combination with any suitable bottle or container containing, e.g., an irrigation solution, and a base. The modular filling station of the invention protects against contamination and allows for time-saving one-hand use without loss of material.
